(57) CLAIM

The ornamental design for a packing box, as shown and described.

DESCRIPTION

FIG. 1 is a front perspective view of a packing box showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an exploded perspective view of the packing box;

FIG. 9 is another perspective view of the packing box illustrating an example environment;

FIG. 10 is another perspective view of the packing box illustrating an example environment; and,

FIG. 11 is another perspective view of the packing box illustrating an example environment.

The broken lines are for environmental purposes only and form no part of the claimed design.
